(57) **CLAIM**

The ornamental design for a notebook computer, as shown and described.

DESCRIPTION

FIG. 1 is a perspective view of a notebook computer showing our new design;

FIG. 2 is another perspective view thereof;

FIG. 3 is another perspective view thereof;

FIG. 4 is another perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is a cross-sectional view taken along line 11-11 in FIG. 7;

FIG. 12 is an enlarged view of the portion, labeled '12' of FIG. 1;

FIG. 13 is an enlarged view of the portion, labeled '13' of FIG. 1;

FIG. 14 is an enlarged view of the portion, labeled '14' of FIG. 2;

FIG. 15 is an enlarged view of the portion, labeled '15' of FIG. 2;

FIG. 16 is an enlarged view of the portion, labeled '16' of FIG. 3;

FIG. 17 is an enlarged view of the portion, labeled '17' of FIG. 3;

FIG. 18 is an enlarged view of the portion, labeled '18' of FIG. 4;

FIG. 19 is an enlarged view of the portion, labeled '19' of FIG. 4;

(Continued)

FIG. 20 is an enlarged view of the portion, labeled '20' of FIG. 6;
 FIG. 21 is an enlarged view of the portion, labeled '21' of FIG. 6;
 FIG. 22 is an enlarged view of the portion, labeled '22' of FIG. 7;
 FIG. 23 is an enlarged view of the portion, labeled '23' of FIG. 8;
 FIG. 24 is an enlarged view of the portion, labeled '24' of FIG. 11; and,
 FIG. 25 is an enlarged view of the portion, labeled '25' of FIG. 11.
 The even-dash broken lines illustrate portions of the notebook computer that form no part of the claimed design. The uneven-dash broken lines define the extents of the detail views and form no part thereof.

1 Claim, 16 Drawing Sheets

(58) Field of Classification Search

CPC G06F 1/1616; G06F 1/1601; G06F 1/1613
